TEMPERATURE CONTROL SYSTEM

Filed July 22, 1933

UNITED STATES PATENT OFFICE

2,036,868

TEMPERATURE CONTROL SYSTEM

Arthur C. Grant, St. Paul, Minn., assignor to
 Minneapolis-Honeywell Regulator Company,
 Minneapolis, Minn., a corporation of Delaware

Application July 22, 1933, Serial No. 681,728

28 Claims. (Cl. 236—11)

The present invention relates to a temperature control system by which a building or space may be automatically heated during the winter and cooled during the summer.

5 One of the objects of the present invention is the provision of a cooling system in which outdoor air is circulated to the building or space to be cooled only in the event that the outdoor temperature is below the desired building or space 10 temperature and particularly when the building or space temperature is above the desired value.

Another object of the invention is the provision 15 of a cooling system for a building or space to be cooled in which air is circulated from a normally cooler part of the building, such as the basement, if the temperature of the building or space becomes higher than that desired.

A further object of the invention is the provision 20 of a cooling system for a building or space in which air is always circulated in the building or space whenever the same is above the desired temperature, said air being selectively taken from the outdoors or from some cooler portion of the building, such as the basement, dependent upon 25 the temperature of the outside air.

Another object of the invention is the provision of humidity changing means in combination with the aforementioned systems.

Other objects of the invention include the 30 specific combinations and sub-combinations of the complete summer-winter system, of the various sub-divisions thereof, and the manner in which the summer-winter change-over is obtained.

35 Further objects of the invention will become apparent as the description thereof proceeds.

For a more complete understanding of the invention, reference may be had to the following 40 description and the accompanying drawing, in which:

Fig. 1 is a schematic representation of the entire system including the details of the electrical connections, and

Fig. 2 is a sectional view taken about on line 45 2—2 of Fig. 1.

Referring to Fig. 1 of the drawing, the building or space the temperature of which it is desired to control both in the summer and in the winter is herein partially shown as comprising a room 50 10 and the usual basement 11, which basement of course has at least a portion thereof below the surface of the ground as is usual in building construction. The temperature control means of the instant invention includes a heating means 55 herein shown as a warm air furnace 12 which is heated by a gas burner (not shown) to which gas is supplied by a gas pipe 13 controlled by an electrically operated gas valve 14 of ordinary construction. A duct 15 is herein shown for allowing air to pass from the room 10 into the

basement 11 although it will be appreciated that under certain conditions this duct 15 may be omitted since the natural filtration between the room 10 and basement 11 may allow sufficient air to pass therebetween. An intake duct 16 supplies air to the furnace 12 and is provided with two branches, one branch 17 being in communication with the basement 11 and the other branch 18 being in communication with the outdoor atmosphere. A blower motor 19 operates a blower 20 through a driving connection 21 so as to force air through the furnace 12 and into a discharge duct 22 which communicates with the room 10. A damper 23 is adapted to selectively close off the outdoor inlet duct 18 or the basement inlet 15 duct 17 and is controlled by a damper motor 24 which operates a crank arm 25 that is connected to a crank 26 by means of a link 27. With the parts in the position shown, when the blower motor 19 is operating, air is drawn into basement 20 inlet duct 17, passes through the furnace 12 and is discharged into room 10 through discharge duct 22. When the damper 23 is moved to its other position and the blower motor 19 is operating, outdoor air is taken into the outdoor intake 25 duct 18, passes through furnace 12 and discharges into room 10 by means of discharge duct 22. Air filters 28 may be placed in inlet duct 16 if it is desired to filter and clean the incoming air.

The damper motor 24 is of a well-known type 30 in which current is supplied thereto by line wires 29 and which is additionally provided with three control wires (to be hereinafter specifically referred to) arranged so that completion of the circuit between two of them causes a one half 35 revolution of crank arm 25 to move damper 23 to its other position, whereas completion of the circuit between two other of the three control wires causes crank arm 25 to return to the position shown in the drawing, all in a manner now 40 well known to those skilled in the art.

The system includes a high limit switch 30, a blower switch 31 and a manually operable switch 32. The high limit switch 30 and blower switch 45 31 are thermostatically controlled by the temperature of the air in furnace 12 or discharge duct 22 in the usual manner and the arrangement is preferably such as shown in John P. Kierchbaum application Ser. No. 678,429 filed June 30, 1933, so that manipulation of a single 50 adjusting handle to summer-position closes manual switch 32, adjusts high limit switch 30 so that it normally remains open-circuited throughout the summer and adjusts blower switch 31 so that it remains closed throughout the summer 55 upon normal temperature fluctuations whereas movement of the adjusting handle to the winter-position opens the manual switch 32 and sets limit switch 30 and blower switch 31 at the proper desired and usual operating temperatures 60

for winter-operation. While the thermostatic switching mechanism that includes switches 30 and 31 preferably takes the form disclosed in said Kriegbaum application, it may well comprise the simpler arrangement shown in Fig. 2. A case 110 is therein shown as being provided with a tubular extension 111 which extends into the bonnet 112 of the furnace 12. A thermostatic element 113 has one of its ends secured to this extension 111 and its other end secured to a torsion rod 114 that extends through the extension 111 and terminates within case 110. A switch arm 115 is secured to the torsion rod 114 and in turn carries the switches 30 and 31.

15 The system of the present invention additionally includes a room thermostat herein shown as a bimetallic volute 33 which moves a contact blade 34 into engagement with cold and hot contacts 35 and 36 respectively upon changes in the temperature of the room 10. The room thermostat controls a relay comprising a pull or energizing coil 37 and deenergizing or bucking coil 38 which coils control an armature 39 that in turn operates switch arms 40, 41 and 42 which are adapted to engage contacts 43, 44 and 45 when armature 39 is attracted upon energization of energizing coil 37. An outdoor thermostat comprises a bimetallic volute 46 in control of a contact blade 47 adapted to engage cold and hot contacts 48 and 49 respectively.

30 The humidity changing means comprises a water spray 50 located in the discharge duct 22 and this water spray 50 is supplied with water by a water pipe 51 which is controlled by an electrically operated water valve 52. A humidostat 53, located in or responsive to the relative humidity of the room 10, partially controls the operation of water valve 52 as will hereinafter become apparent.

40 High voltage supply lines 54 and 55 supply power to the primary 56 of a step-down transformer 57 having a low voltage secondary 58. A relay coil 59 is connected to secondary 58 through manual switch 32 by wires 60, 61 and 62. Relay coil 59 controls an armature 63 which in turn operates switch arms 64, 65, 66 and 67. Relay coil 59 is energized at the present time by reason of closure of the manual switch 32 with the result that switch arm 64 is engaging a contact 68, switch arm 65 is engaging a contact 69 and switch arm 67 is engaging a contact 70. Whenever relay coil 59 is deenergized to release armature 63, switch arm 64 will disengage contact 68 and move into engagement with a contact 71, switch arm 65 will disengage contact 69 and move into engagement with a contact 72, switch arm 66 will move into engagement with a contact 73, and switch arm 67 will disengage contact 70 and move into engagement with a contact 74. Line wires 54 and 55 also furnish power to the high voltage primary 75 of a step-down transformer 76 having a low voltage secondary 77.

60 The remaining circuit connections and the detailed manner in which the system of the instant invention operates and functions will be described under the headings "Summer operation" and "Winter operation".

Summer operation

70 The apparatus as shown in Fig. 1 of the drawing is operating on the summer-cycle in which manual switch 32 is in the closed position, high limit switch 30 is open and remains open under all normal conditions and blower switch 31 is closed and remains closed under all normal con-

ditions. As previously pointed out, the operation of manual switch 32 and adjustment of high limit switch 30 and blower switch 31 is preferably accomplished by a single operation by means of the apparatus disclosed in the aforementioned Kriegbaum application Ser. No. 678,429.

With the parts in the position shown, the room 10 is sufficiently cool since contact blade 34 is in engagement with cold contact 35. Likewise, the outdoor temperature is relatively high since it will be observed that contact blade 47 is in engagement with its hot contact 49. A circuit has therefore been closed to damper motor 24 which circuit includes a wire 78, switch arm 67, contact 70, wire 79, bimetallic volute 46, contact 15 blade 47, hot contact 49, wire 80 and wire 81. Closure of this circuit has operated crank arm 25 to the position shown wherein damper 23 closes off outdoor inlet duct 18. Now if the room temperature should rise, blade 34 will be moved 20 into engagement with the hot contact 36 of the room thermostat and establish an energizing circuit for pull coil 37 as follows: secondary 77, wire 82, wire 83, contact 69, switch arm 65, wire 84, hot contact 36, contact blade 34, bimetallic volute 25 33, wire 85, pull coil 37 and wire 86 to the other side of secondary 77. Armature 39 is thereupon attracted and moves switch arms 40, 41 and 42 into engagement with their respective contacts 43, 44 and 45. Engagement of switch arm 40 with contact 43 establishes a holding circuit for pull coil 37 which is entirely independent of all other switches and is as follows: secondary 77, wire 82, wire 87, switch arm 40, contact 43, pull coil 37 and wire 86 to the other side of secondary 77. Engagement of switch arm 42 with contact 45 will not result in energization of gas valve 14 inasmuch as high limit switch 30 is always open during the summer. Likewise, engagement of switch arm 41 with contact 44 will not result in energization of water valve 52 irrespective of the relative humidity of the room 10 since the circuit to water valve 52 is broken through switch arm 66 and contact 73. If, however, it should be desired to humidify the air during the summer, the switch arm 66 and contact 73 could well be omitted whereupon operation of water valve 52 during the summer would be the same as will be hereinafter described in connection with the winter-operation of the system.

50 Engagement of switch arm 41 with contact 44 does result in energization of blower motor 19 since blower switch 31 is always closed during the summer-operation and this energizing circuit is as follows: line wire 55, wire 88, contact 44, switch arm 41, wire 89, blower switch 31, wire 90, blower motor 19, wire 91 and wire 92 to line wire 54. Energization of blower motor 19 causes the normally cooler air in basement 11 to be drawn into basement inlet duct 17, pass through air filters 28, pass through furnace 12 and discharge duct 22 and into the room 10. In this manner, there will be a continuous circulation of air from the basement 11 and into room 10 so long as the room remains too hot and the outdoor temperature remains too high.

60 In the event that this circulation of basement air to the room 10 lowers the room temperature to such an extent that contact blade 34 returns to the position shown in Fig. 1 of the drawing 70 where it is in engagement with the cold contact 35 of the room thermostat, then a circuit for bucking coil 38 will be established as follows: secondary 77, wire 82, wire 87, switch arm 40, contact 43, wire 85, bimetallic volute 33, contact 75

blade 34, wire 83, switch arm 64, contact 68, wire 24, wire 95, bucking coil 38, wire 96 and wire 86 to the other side of secondary 17. Energization of bucking coil 38 sets up a magnetic flux in opposition to the magnetic flux produced by bucking coil 37 with the result that the two magnetic fluxes neutralize one another and allow armature 39 to return by gravity to the position shown in the drawing. Immediately upon separation of switch arm 40 from contact 43 both the holding circuit for pull coil 37 and the energizing circuit for bucking coil 38 are interrupted so that the parts all assume the positions shown in the drawing. Separation of switch arm 41 from contact 44 deenergizes blower motor 19 and the circulation of air from basement 11 to room 10 is interrupted.

There will be times when the outdoor temperature is relatively low causing contact blade 47 to engage cold contact 48. This will occur particularly during the night. When this condition exists, a new circuit to damper motor 24 including wire 78, switch arm 67, contact 70, wire 79, bimetallic volute 46, contact blade 47, cold contact 48, and wire 97 will be established. This circuit causes damper motor 24 to turn crank arm 25 through one half revolution whereupon damper 23 is moved to its other position to close off basement inlet duct 17 and open outdoor inlet duct 18. Now if the room temperature becomes excessive and contact blade 34 engages hot contact 36, blower 19 will again be put into operation as previously described but air will now be taken from the outdoors through outdoor inlet duct 18 and circulated to the room 10 in order to lower the temperature thereof.

From the foregoing description of the operation, it will be seen that blower motor 19 is operated whenever the room temperature becomes excessive in the summer and the damper 23 is selectively positioned to allow air to be circulated to room 10 either from the basement 11 or from the outdoors, depending upon the outdoor temperature. Preferably the outdoor thermostat is so adjusted that outdoor air may be circulated to the room 10 whenever the room 10 is too hot and whenever the outdoor temperature is below the desired room temperature but if the outdoor temperature is above the desired room temperature, then the natural cool air of the basement 11 is circulated to the room 10 in an effort to reduce its temperature to the desired value.

It will therefore be seen that the present invention contemplates cooling a building or space by means of the outdoor air whenever the temperature of the outdoor air is sufficiently low. It will also be seen that the present invention contemplates cooling a room or space by circulating air from a naturally cooler portion of the building whenever the temperature of the space to be cooled becomes excessive. The invention further contemplates a combination of these two systems whereby outdoor air will be circulated to the space to be cooled when the outdoor temperature is sufficiently low to have a cooling effect on the space but when the outdoor air is too high in temperature to have a cooling effect, the basement air is automatically substituted for the outdoor air.

Winter operation

During the winter, manual switch 32 is opened, blower switch 31 is adjusted so that it is only closed when the temperature of the air circulated

to room 10 is sufficiently high and high limit switch 30 is adjusted so that it is normally closed but opens if the temperature of the air circulated to room 10 or if some other furnace condition becomes excessive. Opening of manual switch 32 deenergizes relay coil 59 whereupon switch arm 64 moves into engagement with contact 71, switch arm 65 moves into engagement with contact 72, switch arm 66 moves into engagement with contact 73 and switch arm 67 moves into engagement with contact 74. Engagement of switch arm 66 with contact 73 conditions water valve 52 for operation. Engagement of switch arm 67 with contact 74 closes the circuit between control wires 78 and 81 of damper motor 24 and maintains the circuit closed throughout the winter so that the damper 23 will close off outdoor inlet duct 18 irrespective of the outdoor temperature since the circuit to blade 47 has been interrupted by movement of switch arm 67 out of engagement with contact 70. Disengagement of switch arm 64 from contact 68 and engagement thereof with contact 71 and disengagement of switch arm 65 from contact 69 and engagement thereof with contact 72 reverses the operation of the room 25 thermostat in respect to the pull and bucking coils 37 and 38 as will be apparent as the description of the winter operation proceeds.

When the room 10 becomes cold, contact blade 34 will engage cold contact 35 to establish an energizing circuit for pull coil 37 as follows: secondary 17, wire 82, wire 83, contact 71, switch arm 64, wire 93, cold contact 35, contact blade 34, bimetallic volute 33, wire 85, pull coil 37 and wire 86 to the other side of secondary 17. It will be noted that pull coil 37 is energized when the room temperature is too low in the winter whereas pull coil 37 is energized when the room temperature is too high in the summer. Energization of pull coil 37 moves switch arms 40, 41 and 42 into engagement with contacts 43, 44 and 45 as before pointed out. Engagement of switch arm 40 with contact 43 establishes the heretofore described holding circuit for pull coil 37 which is independent of all other switches. Engagement of switch arm 42 with contact 45 energizes gas valve 14 to supply gas to the furnace 12 by a circuit as follows: line wire 55, wire 99, contact 45, switch arm 42, wire 100, high limit switch 30, wire 101, gas valve 14 and wire 102 to line wire 54. Heat will therefore be supplied to the furnace 12 provided the temperature thereof or the temperature of the air to be circulated to the room 10 is not already excessive so as to cause opening of limit switch 30.

Engagement of switch arm 41 with contact 44 will condition blower motor 19 for operation whenever the temperature of the air to be circulated to room 10 is sufficiently high as indicated by closure of blower switch 31 and the closure of blower switch 31 taken together with engagement of switch arm 41 with contact 44 conditions water valve 52 for operation at the command of the humidostat 53. If blower switch 31 now closes, blower motor 19 will be energized by the circuit previously described in connection with the summer operation of the system.

If the relative humidity of the room 10 is too low at any time that blower motor 19 is in operation, the water valve 52 will be energized to supply water to the spray 50 by a circuit as follows: line wire 55, wire 88, contact 44, switch arm 41, wire 89, blower switch 31, wire 103, humidostat 53, wire 104, switch arm 66, contact 73, wire 105, water valve 52, wire 106, and wire 92 to line wire 54.

It will be noted that during the winter, blower motor 19 can only operate when the room is cold and when blower switch 31 is closed and it will also be noted that water can only be supplied to spray 50 when blower motor 19 is operating and when the relative humidity to which humidostat 53 responds is below the desired point.

If the temperature of the furnace 12 or of the air delivered to room 10 should become excessive, limit switch 30 will open in the usual manner to deenergize gas valve 14 and turn off the supply of gas to the furnace.

Whenever the room temperature rises to the desired point, contact blade 34 will engage hot contact 36 to energize bucking coil 38 by the following circuit: secondary 11, wire 82, wire 81, switch arm 40, contact 43, wire 85, bimetallic volute 33, contact blade 34, hot contact 36, wire 84, switch arm 65, contact 72, wire 95, bucking coil 38, wire 96, and wire 86 to the other side of secondary 11. Energization of bucking coil 38 allows armature 39 and the associated switch arms to return to the position shown in the drawing in the manner described in connection with the summer operation of the system so as to render water valve 52, blower motor 19 and gas valve 14 inoperative until the room 10 again becomes cold and causes contact blade 34 to again engage cold contact 35.

From the foregoing description of the winter operation of this system, it will be noted that the system of the present invention provides a year around temperature control which operates to heat a room or space in the winter time and to cool it in the summer time and the change-over between summer and winter operation is simply accomplished by the manual operation of switch 32, blower switch 31 and high limit switch 30, all of which may be controlled by a single operation if desired in the manner set forth in the aforementioned Kriechbaum application.

While a specific embodiment of this complete summer-winter control system has been herein described, it will be understood that changes can be readily made in either the summer-operation or in the winter-operation or in the combination of the two systems and I therefore only intend to be limited in the purview of the appended claims.

I claim as my invention:

1. A system of the class described, comprising, in combination, a space to be cooled, a duct connecting said space to the outside atmosphere, an electrically operated blower for circulating air from the outside atmosphere through said duct and into said space, a thermostatic switch responsive to the temperature of the outside atmosphere for preventing circulation of outside air into said space if the temperature of the outside atmosphere is above a predetermined value and manually operable switching means associated with said thermostatic switch for rendering the same incapable of permitting circulation of outside air to said space irrespective of the outside temperature.

2. A system of the class described, comprising, in combination, a space to be cooled, a duct connecting said space to the outside atmosphere, means for circulating air from the outside atmosphere through said duct and into said space, a space temperature responsive thermostat for operating the circulating means when the temperature of the space rises above a given value, thermostatic means responsive to the temperature of the outside atmosphere for preventing circulation of air from the outside atmosphere and

into said space if the temperature of the outside atmosphere is above the desired space temperature, and two-position manual means associated with said thermostatic means for rendering the same incapable of permitting circulation of outside air to said space irrespective of the temperature of the outside air.

3. A system of the class described, comprising in combination, a first space which it is desired to cool, a second space located at least partially below the surface of the ground, duct means inter-connecting said first space, the second space and the outside atmosphere, damper means co-operating with said duct means and operable to selectively connect said first space with the second space or the outdoors, a thermostat responsive to outdoor temperature in control of said damper means to connect the outdoors with the first space when the outdoor temperature is below a given value and to connect the second space to the first space when the outdoor temperature rises above said value, circulating means for circulating air through said duct means and into said first space, and a thermostat responsive to the temperature of said first space for operating said circulating means when the temperature of the first space is above a predetermined value.

4. A system of the class described, comprising in combination, a first space which it is desired to cool, a second space located at least partially below the surface of the ground, duct means inter-connecting said first space, the second space and the outside atmosphere, damper means co-operating with said duct means and operable to selectively connect said first space with the second space or the outdoors, a damper motor operatively connected to the damper means, a thermostat responsive to outdoor temperature in control of said damper motor to operate said damper means to connect the outdoors to the first space when the outdoor temperature is below a given value and to connect the second space to the first space when the outdoor temperature rises above said value, a blower for circulating air through said duct means and into said first space, and a thermostat responsive to the temperature of said first space for operating said blower when the temperature of the first space is above a predetermined value.

5. A system of the class described, comprising in combination, a first space which it is desired to cool, a second space located at least partially below the surface of the ground, duct means inter-connecting said first space, the second space and the outside atmosphere, damper means co-operating with said duct means and operable to selectively connect said first space with the second space or the outdoors, a thermostat responsive to outdoor temperature in control of said damper means to connect the outdoors to the first space when the outdoor temperature is below a given value and to connect the second space to the first space when the outdoor temperature rises a predetermined amount above said value, an electrically operated blower for circulating air through said duct means and into said first space, and thermostatic switching means responsive to the temperature of said first space for operating said blower when the temperature of the first space is above a predetermined value.

6. A temperature control system of the class described, comprising, in combination, a space the temperature of which it is desired to control, duct means connecting said space to the outdoors, damper means associated with said duct

means and operable to permit or prevent circulation of air from the outdoors to said space, a thermostat responsive to the outdoor temperature for operating said damper means to prevent circulation of air from the outdoors to said space when the temperature of the outdoor air is above a predetermined value during the summer and and two-position manually operable means for changing the connections to the damper means in such manner that the latter prevents circulation of air from the outdoors to the space at all times in the winter.

7. In combination, a space the temperature of which it is desired to control, a thermostat responsive to the temperature of the space, a blower for circulating air to said space, means for heating the air circulated to the space, connections between the space thermostat and blower for operating the latter when the space temperature falls below the desired value, manually operable means for changing said connections in such manner that the space thermostat operates said blower when the space temperature becomes too high in the summer, a thermostat responsive to outdoor temperatures, damper means controlled by said outdoor thermostat for permitting circulation of outdoor air to said space when the outdoor temperature is below the desired space temperature in the summer, and connections between said manually operable means and outdoor thermostat for rendering the latter incapable of operating the damper means to permit circulation of outdoor air to said space when said manually operable means is in winter position.

8. In combination, a space the temperature of which it is desired to control, a thermostat responsive to the temperature of the space, a blower for circulating air to said space, means for heating the air circulated to the space, connections between the space thermostat, heating means, and blower for operating the heating means and blower when the space temperature falls below the desired value, high limit means responsive to the temperature of the heated air for preventing operation of the heating means if the temperature of the heated air is too high, manually operable means for changing said connections in such manner that the space thermostat operates said blower when the space temperature becomes too high in the summer and for adjusting said high limit means to prevent operation of the heating means in the summer, a thermostat responsive to outdoor temperatures, damper means controlled by said outdoor thermostat for permitting circulation of outdoor air to said space in the summer by said blower when the outdoor temperature is below the desired space temperature and connections associated with said damper means and manually operable means for preventing operation of the damper means to permit circulation of outdoor air to said space in the winter under the control of said outdoor thermostat.

9. In combination, a space the temperature of which it is desired to control, a thermostat responsive to the temperature of the space, a blower for circulating air to said space, means for heating the air circulated to the space, connections between the space thermostat and blower for operating the latter when the space temperature falls below the desired value, manually operable means for changing said connections in such manner that the space thermostat operates said blower when the space temperature

becomes too high in the summer, a thermostat responsive to outdoor temperatures, damper means controlled by said outdoor thermostat for permitting circulation of outdoor air to said space when the outdoor temperature is below the desired space temperature in the summer and for preventing such circulation upon operation of said manually operable means to winter position, humidity changing means associated with the circulated air, a humidistat responsive to the relative humidity in said space, and connections between said humidistat, space thermostat and humidity changing means.

10. In combination, a first space the temperature of which is to be controlled, a second space which is generally cooler in the summer than said first space, a thermostat responsive to the temperature of said first space, a blower for circulating air from said second space to said first space, means for heating said air, connections between said space thermostat, blower, and heating means for operating the blower and heating means when the temperature of said first space drops to a predetermined minimum in the winter, and manually operable means for rearranging said connections in such manner that the blower is operated upon rise in the space temperature to a given value and the heating means is rendered inoperative in the summer, whereby the air is circulated from said cooler second space to said first space at the command of said space thermostat in the summer.

11. In combination, a first space the temperature of which is to be controlled, a second space which is generally cooler in the summer than said first space, a thermostat responsive to the temperature of said first space, a blower for circulating air from said second space to said first space, means for heating said air, connections between said space thermostat, blower, and heating means for operating the blower and heating means when the temperature of said first space drops to a predetermined minimum in the winter, high limit means responsive to the temperature of the circulated air for preventing operation of the heating means if the temperature of the heated air is too high, and manually operable means for rearranging said connections and adjusting said high limit means in such manner that the blower is operated upon rise in the space temperature to a given value and the heating means is rendered inoperative during the summer, whereby the air is circulated from said cooler second space to said first space at the command of said space thermostat in the summer.

12. In combination, a first space the temperature of which is to be controlled, a second space which is generally cooler in the summer than said first space, a thermostat responsive to the temperature of said first space, a blower for circulating air from said second space to said first space, means for heating said air, connections between said space thermostat, blower, and heating means for operating the blower and heating means when the temperature of said first space drops to a predetermined minimum in the winter, a blower controller responsive to the temperature of the heated air for preventing operation of the blower if the temperature of the circulated air is below a given value, and manually operable means for rearranging said connections and adjusting said blower controller in such manner that the blower is operated upon rise in the space tem-

- perature to a given value irrespective of normal fluctuations in the circulated air temperature and the heating means is rendered inoperative whereby air is circulated from said cooler second space to said first space at the command of said space thermostat in the summer.
13. A summer-winter control system of the class described, comprising, in combination, a building including a basement and a space the temperature of which it is desired to control, duct means inter-connecting said space, basement and the outdoors, damper means associated with said duct means and operable to selectively connect said space with the basement or outdoors, a blower for circulating air through said duct means and into said space, means for heating the air circulated to said space, a space temperature responsive thermostat, connections between the space thermostat and blower for operating said blower upon fall in space temperature to maintain the desired space temperature during the winter, manually operable means for rearranging said connections in such manner that the blower is operated upon rise of the space temperature in the summer, and a thermostat responsive to the outdoor temperature for operating said damper means to connect the outdoors to the space when the outdoor temperature is lower than the desired space temperature in the summer and rendered operable by said manually operable means.
14. A summer-winter control system of the class described, comprising, in combination, a building including a basement and a space the temperature of which it is desired to control, duct means inter-connecting said space, basement and the outdoors, damper means associated with said duct means and operable to selectively connect said space with the basement or outdoors, a blower for circulating air through said duct means and into said space, means for heating the air circulated to said space, a space temperature responsive thermostat, connections between the space thermostat, heating means and blower for operating the heating means and blower whereby to maintain the desired space temperature during the winter, manually operable means for rearranging said connections in such manner that the blower is operated upon rise of the space temperature in the summer, a thermostat responsive to outdoor temperature for operating said damper means to connect the outdoors to the space when the outdoor temperature is lower than the desired space temperature in the summer, rendered operative by said manually operable means, humidity changing means associated with said duct means, and a humidostat in control thereof.
15. A summer-winter control system of the class described, comprising, in combination, a building including a space the temperature of which it is desired to control and a basement, a warm air furnace located in the basement, a duct connecting said warm air furnace to the space, duct means interconnecting said warm air furnace, the interior of the basement, and the outdoor atmosphere; an electrically operated blower associated with said furnace and ducts for circulating air through the furnace and into said space, electrically controlled means for heating the air circulating through the furnace, thermostatic switching means responsive to the temperature of the space, connections between said thermostatic switching means, heating means and blower for operating the heating means and blower to supply heated air to said space when the space temperature falls below the desired value in the winter, a high limit switch in circuit with said heating means and responsive to the temperature of the heated air for preventing operation of the heating means if the temperature of the circulated air becomes too high, a blower switch responsive to the temperature of the circulated air for preventing operation of the blower if the temperature of the circulated air is too low, manually controlled means for adjusting said high limit switch and blower switch and for rearranging the connections to the space temperature responsive switching means in such manner that operation of the heating means is prevented and the blower is operated upon fall in the space temperature irrespective of normal fluctuations in the temperature of the circulated air, damper means associated with said duct means and selectively operable to connect said furnace with the outdoor atmosphere or the interior of said basement, and a thermostat responsive to the outdoor temperature adapted to be placed in control of said damper means for connecting the outdoor atmosphere to the furnace when the outdoor temperature is below the desired space temperature and for connecting the furnace to the interior of the basement when the outdoor temperature is above the desired space temperature during the summer, said manually operable means serving to place said outdoor thermostat in control of said damper means when in summer position.
16. A system of the class described, comprising, in combination, a first space which it is desired to cool, a second space normally cooler than said first space in the summer, duct means interconnecting the first space, second space, and the outside atmosphere, means for controlling the circulation of air from the outside atmosphere and from said second space to said first space and an outdoor temperature responsive thermostat in control of said means.
17. A system of the class described, comprising, in combination, a first space which it is desired to cool, a second space normally cooler than said first space in the summer, duct means interconnecting the first space, second space, and the outside atmosphere, damper means for controlling the circulation of air from the outside atmosphere and from said second space to said first space, an outdoor temperature responsive thermostat in control of said damper means, and a blower for causing circulation of air through said duct means.
18. In combination, a building including a basement and a space the temperature of which it is desired to control, duct means inter-connecting said space, basement and the outdoors, circulating means for causing a circulation of air through said duct means to said space, damper means controlling the flow of air from the outdoors or basement to said space, an outdoor thermostat in control of said damper means for operating the same to permit the circulation of outdoor air to said space in the summer when the outdoor air is below the desired value, means for heating the air delivered to said space in the winter, and manually operable means associated with said heating means and outdoor thermostat for rendering said heating means inoperative when moved to its summer position and for preventing operation of said damper means by said outdoor thermostat to permit circulation of outdoor air in the winter when moved to its winter position.

19. In combination, a building including a basement and a space the temperature of which is desired to control, duct means inter-connecting the space, basement and outdoors, a blower 5 for circulating air through said duct means to said space, electrically operated heating means for heating the air circulated to said space, a space temperature responsive switching mechanism, electrically operated damper means controlling the circulation of air from the outdoors and basement to said space, an outdoor temperature responsive switching mechanism, manually operable switching mechanism having a winter position and a summer position, electrical connections between said space thermostat, heating means and manually operable switching mechanism for enabling said thermostat to operate said heating means when the manually operable switching mechanism is in winter position, and 10 connections between said outdoor thermostat, damper means and manually operable switching mechanism for enabling said outdoor thermostat to operate said damper means to permit circulation of outdoor air to said space when the outdoor air is below the desired space value and the manually operable switching mechanism is in summer position. 15
20. A cooling system of the class described, comprising, in combination, a building including a space to be cooled and a basement, means in control of the circulation of air from the basement to said space, and an outdoor temperature responsive thermostat associated with said means for controlling the same to permit circulation of air from said basement to said space when the outdoor temperature rises to a given value. 20
21. A cooling system of the class described, comprising, in combination, a building including a space to be cooled and a basement, duct means connecting said space and basement, damper means for opening said duct means to permit circulation of air from the basement to said space, and an outdoor temperature responsive thermostat associated with said damper means for operating the same to open said duct means when the outdoor temperature rises above a predetermined value. 25
22. The combination with a first space to be controlled and a second space which is normally cool in the summer, of circulation controlling means in control of the flow of air to the first space from the second space and the outdoors, an outdoor temperature responsive thermostat in control of said circulation controlling means, and means to prevent operation of the circulation controlling means by the outdoor temperature responsive thermostat irrespective of the value of the outdoor temperature. 30
23. The combination with a first space to be controlled and a second space which is normally cool in the summer, of damper means to control the flow of air to said first space from the second space and the outdoors, an outdoor temperature responsive thermostat in control of said damper means, and means to place said damper means in a predetermined position at all times irrespective of the value of the outdoor temperature. 35
24. The combination with a first space to be controlled and a second space which is normally cooler than the first space, of circulation con-
- trolling means in control of the circulation of air to the first space from the second space, an outdoor temperature responsive thermostat in control of said circulation controlling means, and means to prevent such control by the outdoor thermostat. 40
25. The combination with a first space to be cooled and a second space which is normally cooler than the first space, of circulation controlling means in control of the flow of air from said second space and the outside atmosphere to said first space, thermostatic means responsive to the temperature of the first space and the outdoors, and connections between said thermostatic means and circulation controlling means to cause circulation of air to said first space when the temperature thereof becomes too high and to select such air from the second space and the outdoors in response to changes in outdoor temperature. 45
26. The combination with a first space to be cooled and a second space which is normally cooler than the first space, of circulation controlling means in control of the flow of air from said second space and the outside atmosphere to said first space, thermostatic means responsive to the temperature of the first space and the outdoors, connections between said thermostatic means and circulation controlling means to cause circulation of air to said first space when the temperature thereof becomes too high and to select such air from the second space or the outdoors in response to changes in outdoor temperatures, and means to change the control action of the thermostatic means to cause air to be circulated to said first space from said second space upon a fall in the temperature of the first space and irrespective of the temperature of the outdoor air. 50
27. In combination, circulation controlling means in control of the flow of air to a space, means to humidify such air, a space humidity responsive element to control said humidifying means, a space temperature responsive device to operate the circulation controlling means and to place the humidity responsive element in control of the humidifying means upon a lowering in space temperature, and a single means operable to reverse the action of the space temperature responsive device on the circulation controlling means and to prevent operation of the humidifying means by the humidity responsive element. 55
28. A temperature control system of the class described, comprising, in combination, damper means in control of the flow of outdoor air to a space to be controlled, a thermostat responsive to outdoor temperature in control of said damper means to prevent the circulation of outdoor air to the space when the outdoor air temperature is too high in the summer, heating means to heat the air, a space temperature responsive thermostat, and a single means operable to move the damper means to a position to prevent the circulation of outdoor air to said space irrespective of the outdoor temperature and to place the space thermostat in control of the heating means to operate the same upon a fall in space temperature to a predetermined point. 60
